VERTICAL DRIER

Charles A. Dickhaut and Sterling W. Warner,
New Brunswick, N. J., assignors to John Wal-
dron Corporation, New Brunswick, N. J., a cor-
poration of New Jersey

Application April 11, 1936, Serial No. 73,878

8 Claims. (Cl. 34—48)

This invention relates to vertical driers for coated paper, textiles, and other web material. Coated paper is dried in various forms of driers such as festoon driers wherein paper is carried in festoons on sticks or in floating driers where the paper is supported by air pressure or is dried when only coated on one side by drying drums. In many forms of coating such as in the case of varnishes, lacquers and emulsions, the coatings become tacky when partially dried and hence can only be coated on one side otherwise the web will adhere to the sticks. It, therefore, is necessary to coat one side and dry same, and then to coat the other side. As the length of time required for oxidizing necessitates a rather slow speed a double coating materially increases the cost. Even where only one side is coated and dried at one time, the stick mark settings are sometimes discernible. Where attempts have been made to dry the web by suspension from one edge, the contraction of the web in drying is sufficiently great to create wrinkles, marring of the coating and considerable wastage by breakage. Attempts to overcome this by releasing the gripping mechanisms and then regripping the web have not been entirely successful due to the fall of the web upon release of the gripping means. This variation of the edge from a horizontal plane causes an unevenness and a distortion of the web.

One of the objects of this invention is to provide a drier for coated paper and the like that may be coated on both sides and dried in a relatively small space.

Still another object of the invention is to provide a drier wherein paper or the like after being coated may be dried on edge regardless of the width of the paper.

A still further object of the invention is to provide a vertical drier wherein the web during drying may be relieved of the strain set up by the contraction while at the same time the travelling web is maintained at the same level.

A still further object of the invention is to provide a drier that is adapted to dry paper coated with any material economically and efficiently whether coated on one side or both sides.

Referring to the drawing:

Figure 1 is a plan view of a coating and drying device embodying the principles of our invention.

Figure 2 is a detail view of the spiked wheel transfer means.

Figure 3 is a detail view of a modified form of transfer means.

In carrying out our invention, we propose to provide a chamber 1 within which any arrangement of drying medium may be used such as steam, hot air, etc.

We have provided pipes 2 in Figure 1 for the drying medium. Doors 3 function to permit entry into the drying chamber and also as vents. Chamber 1 contains a plurality of passes of a travelling carrier 4 wherein the web of paper 14 is carried by the usual gripper mechanisms secured to travelling carrier 4. A carrier 5 operates from the unwind mechanism 7 around sprocket 6 where the web is automatically gripped and carried through chamber 1 around sprockets 8 and 9, and thence exteriorly of chamber 1 around sprockets 10, 11, 12 and 13, and thence back through chamber 1 and around sprocket 6. At sprocket 11, the carrier 5 leaves the web 14. The web 14 passes through vertical coater rolls 15 and is again picked up by carrier 5 adjacent sprocket 13 where it is carried by carrier 5 through chamber 1 for the initial drying. Any well known means are utilized for maintaining carrier 5 taut, such as a tension means between sprocket 12 and tension device 16. Carrier 5 is generally operated at a greater speed than carrier 4. Carrier 4 is generally maintained at a constant speed. As carrier 5 is an independent carrier its speed can be varied with respect to the speed of carrier 4. The carrier 5 maintains the coated web quite taut. This is partially due to the drying effect. We have found that the major part of the shrinkage of the web after coating and during drying will occur in the first pass, that is, while being borne by carrier 5. Therefore, if the tension of the web is relieved after the initial drying no further transfers are required. In addition, as the carrier 4 is travelling at a lesser speed than carrier 5, there will be sufficient looseness of the web to permit the web to make the returns for the various passes of carrier 4 without the web tearing from the grippers or the grippers becoming opened.

After carrier 5 leaves chamber 1 with the coated web the web passes around spiked wheel 17 where it is imbedded thereon by brush wheel 18. In the modified form shown in Figure 3, the brush wheel 18 is replaced by a grooved wheel 23. Carrier 4 passing around sprocket wheel 22 has the grippers pick up web 14 from spiked wheels 17. The speed of carrier 4 being less than carrier 5, relieves the tension in web 14 eliminating the strain and any wrinkles with the web sufficiently loose to permit reversal for the required number

- of passes through chamber 1. Web 14 then passes out of chamber 1 to rewind mechanism 19. Carrier 4 leaves the web at sprocket 20 to again complete its cycle. Utilization of the transfer means shown prevents the slipping of the material during the transfer operation and the maintenance of the material at the proper level. The maintenance of the edge of the web in the same horizontal plane with relief of tension occasioned by contraction on drying are vital elements in successfully drying coated paper and the like in the vertical plane. Furthermore, the paper must have a certain amount of moisture driven off before the tension is relieved since certain papers when wet have very little strength and a release of the grippers with subsequent regripping while wet will tear the web. In our invention, the necessary amount of moisture is driven off prior to the regripping of the web.
- 20 Various modifications may be made and still fall within the scope of our invention. For instance, the unwind web mechanism may be placed adjacent the coating mechanism and in such case there will be no preliminary drying. We preferably dry the web preliminary to coating so that there will be a better bonding effect between the coating and the web and a more uniform weight of coated paper will be produced. Also variations in coating mechanisms may be utilized. Any well known type of gripping means or carrier chains may be used.
- What we claim is:
1. In a drier, a drying chamber, a plurality of carriers having mechanisms for gripping by one edge a vertical web of material and transporting the same through said chamber, means for transferring said web from one carrier to another, and means for operating said carriers at different speeds.
  2. In a drier, a drying chamber, a single pass continuous carrier having mechanisms for gripping by one edge a vertical web of material and transporting the same through said chamber, a second continuous carrier with a plurality of passes and having mechanisms for supporting by one edge a vertical web of material, said second carrier being motivated at a lesser speed than said first carrier, and means for transferring said web from said first carrier to said second carrier without slippage or breakage of said web.
  3. In a drier, a drying chamber, means for carrying a web of material through said chamber for preliminary drying after treatment, means for carrying said web a plurality of passes through said chamber for additional drying, and means for transferring said web from one carrying means to another, said transfer means including a pinwheel and cooperating means for impaling the web on said pinwheel.
  4. In a drier, a drying chamber, means for carrying a web of material through said chamber

5 for preliminary drying after treatment, means for carrying said web a plurality of passes through said chamber for additional drying, said initial carrying means being motivated at a greater rate of speed than said additional carrying means, 5 means for transferring said web from one carrying means to another, said transfer means comprising a pinwheel and a brush wheel for impaling said web on said pinwheel.

6. In a drier, a drying chamber, means for 10 carrying a web of material through said chamber for preliminary drying after treatment, means for carrying said web a plurality of passes through said chamber for additional drying, said initial carrying means being motivated at a greater rate 15 of speed than said additional carrying means, and means for transferring said web from one carrying means to another, said transfer means comprising a pinwheel and a grooved wheel cooperating 20 therewith to impale said web on said pinwheel.

6. In a drier, a drying chamber, a web-treating mechanism, an unwind mechanism for a web of material, means for carrying said web in vertical position from said unwind mechanism through said drying chamber for preliminary drying to 25 said web treating mechanism and thence again through said drier for an initial drying of said treated web, additional means for carrying said web in vertical position and at a slower speed over a plurality of passes through said drier, and means for transferring said web from one carrying 30 means to the other.

7. In a drier, a drying chamber, a web-treating mechanism, an unwind mechanism for a web of material, means for carrying said web of material in vertical position from said unwind mechanism through said drying chamber for preliminary drying to said web treating mechanism and thence again through said drying chamber for an initial drying of said treated web, additional 40 means for carrying said treated web in vertical position at a slower speed a plurality of passes through said drier, and means for transferring said web from one carrying means to the other, said transferring means comprising a pinwheel 45 and an impaling wheel for impaling said web on said pinwheel.

8. In a drier, a drying chamber, an unwind mechanism for a web of material, a web-treating mechanism, means for carrying said web in vertical position from said unwind mechanism to said treating mechanism and thence through said drier for initial drying of the treated web, additional means for carrying said web in vertical position and at a slower speed over a plurality of 55 passes through said drier, and means for transferring said web from one carrying means to the other.
